Specification for Design.

Patented Aug. 9, 1910.

Application filed April 18, 1908. Serial No. 427,950. Term of patent 14 years.

To all whom it may concern:

Be it known that I, JEAN PETTAVEL, a citizen of the Swiss Republic, and a resident of Fleurier, Neuchâtel, Switzerland, have invented a new, original, and ornamental Design for a Bridge-Plate for Watch-Movements, of which the following is a specification, reference being had to the accompanying drawing, forming part thereof.

The figure is a plan view of a bridge-plate, showing my new design.

I claim:

The ornamental design for a bridge-plate for watch-movements, as shown.

JEAN PETTAVEL.
